UNITED STATES PATENT OFFICE.

FREDERICK W. PARSONS, OF TARRYTOWN, NEW YORK.

PNEUMATIC-MOTOR TOOL-STOCK.

No. 821,960.

Specification of Letters Patent.

Patented May 29, 1906.

Application filed January 7, 1905. Serial No. 240,013.

To all whom it may concern:

Be it known that I, FREDERICK W. PARSONS, a citizen of the United States, residing at Tarrytown, in the county of Westchester 5 and State of New York, have invented certain new and useful Improvements in Pneumatic-Motor Tool-Stocks, of which the following is a specification.

This invention relates to improvements in 10 portable tools which are driven by compressed air and used for drilling, reaming, tapping, and like operations.

One object of my improvements is to provide a tool of this character which shall be 15 compact in form and of large power in proportion to its weight and bulk; and a further object is to shorten the distance between the point of the feed-nut and the extremity of the tool-socket in order that the tool-stock 20 may be operated to advantage in narrow and constricted quarters.

It is also my object to improve in certain 25 details the tool-stock shown and described in Letters Patent of the United States No. 725,127, issued to the Imperial Pneumatic Tool Company, April 14, 1903, for motor for portable tools.

I attain my objects by means of the arrangement and construction of the several 30 parts of the tool, as illustrated in the accompanying drawings, in which—

Figure 1 represents a vertical transverse section through a pneumatic drill-stock embodying my improvements; Fig. 2, an interior view of the casing, with all running parts removed; and Fig. 3 a detail showing means for preventing movement of the gear-ring within the casing.

Like numerals designate like parts in the 40 several views.

The casing of the drill is formed in two parts—the shell 1, having a head integrally formed therewith, and a removable cap or head 2, screw-threaded upon the open end of 45 the shell. At diametrically opposite sides of the shell are bosses, into one of which is fastened the handle 3 and the other of which constitutes a valve-chamber for my improved throttle and reversing valve, which 50 valve is described and claimed in an application for Letters Patent of the United States, filed of even date herewith. The valve-chamber is completed by a valve-sleeve 4, screwed thereinto after the valve 5 is in place 55 within the chamber. The sleeve 4 projects a

sufficient distance beyond the casing-boss to form a handle to correspond with the handle 3. The valve is operated by means of a loose sleeve 6, which is fitted over the sleeve 4 and engages a pin 7, projecting from the 60 valve. The sleeve 4 is provided with a transverse slot where the pin 7 passes through it, so as to permit the requisite turning of said pin in either direction to shift the valve.

From the chambered boss the passages 8 65 and 9 rise parallel to one another on the outside of the casing and connect with the inclined passages 10 and 11, which run over the top or head of the casing to near the center thereof, where they communicate with the 70 inclined passages 13 and 14, formed in the boss 15 at the center of the casing-head. These passages 8, 9, 10, and 11 are formed by drilling them through ribs cast on the casing, the openings left by the drill when forming the passages being closed by screw-plugs. The plugs 12 are provided with knurled 75 heads, so that they may be removed for the purpose of introducing oil for lubricating the motor-cylinders.

The motor is of the rotary reciprocating type and is supported from the boss 15 of the casing-head upon the crank-pin 17, formed with side frame-bearings 16 and 18 at each end. The bearing 16 is secured to the boss 85 15 by means of a stud 22, which is fastened in place by means of a cup-shaped nut 23, which enters a recess formed in the top of the boss. The feed-screw 24 screws onto the stud 22 and enters into the nut 23, forming therewith 90 a jam-nut to securely fasten the crank-pin in place. The feed-nut 25 runs down the feed-screw 24 and into the nut 23 when in its innermost position, said feed-nut being operated by means of handles 26. By the use of the 95 chambered nut 23, which passes into the boss 15, I am enabled to run the feed-nut down close to the motor-support, and therefore materially reduce the distance between the point of the feed-nut and the casing-head 100 without diminishing the feed adjustment.

The motor comprises the cylinders 21, mounted upon and revolving about the stationary crank-pin 17 and coupled to the side frames 19 and 20 in a manner to produce 105 revolution when air is admitted to the cylinders through properly-disposed ports in the crank-pin, said ports being in communication with the passages 13 and 14 by way of vertical passages drilled into the crank-pin. 110

Motion is imparted to the cylinders and side frames by means of the connecting-rods and crank-arms, by which the pistons and cylinders are coupled to the side frames. The 5 general construction of the motor in this respect is not new and needs no further description here. The side frame 19 runs on a flanged bronze ring on the bearing 16, and the side frame 20 runs on the small bearing 18, being provided with a bronze bushing where its hub rides upon said bearing.

The hub 27 on side frame 20 projects beyond the bearing 18 and is provided with an 15 inturned flange at the end, into which one end of the driving-pinion 28 is inserted. In order to secure the pinion to the hub 27, the teeth of the pinion are cut down slightly at the end and are inserted in corresponding notches cut in the inturned flange on the hub. Before 20 the side frame 20 is set in place on the bearing 18 a screw 29 is inserted in the hub, and by said screw the pinion is drawn up into place and fastened in the end of the hub. When the side frame is in place on its bearing, the screw 29 cannot work loose, and the 25 pinion is therefore securely locked to the side frame.

The driving-pinion 28 meshes with a series 30 of intermediate gears 30, preferably three in number, although I have shown but one in the drawings, said intermediate gears engaging the gear-ring 31. This gear-ring is made separate from the casing and is inserted through the open end, being held in place between the lugs 35, cast on the inner wall of 35 the casing, and the gear-head 33. This gear-head 33 has attached to it the gears 30 by means of pins 32, and it is supported and journaled in the casing-head 2. The hub 37 of this gear-head passes out through a central 40 stuffing-box 38 in the casing-head, and its rim rides upon a bronze bearing-ring 34, set into the inner side of the casing-head. The periphery of the gear-head has formed upon it a ball-race in the shape of a right-angled 45 groove, and the gear-ring 31 is provided with a corresponding ball-race on its inner periphery. The chuck or tool-holder 40 is squared or otherwise angled at the end to engage a corresponding squared or angular hole in the hub 37, and a lock-nut 41 is screwed up 50 against a collar formed on the tool-holder to fasten it to the hub. In order to prevent the oil which is contained in the drill-casing 55 from leaking through the joint between the tool-holder and hub 37, a beveled groove is cut around the inner end of the hole in said hub, and a disk 39 is sprung thereinto, thereby forming an oil-tight joint at this point. To 60 prevent the gear-ring 31 from turning in the casing, a toothed locking-plate 36 is riveted to the side of the casing, the teeth of said plate engaging corresponding notches cut in the outer periphery of the gear-ring, as 65 shown in Fig. 3.

To reduce weight in the several parts, all unnecessary metal is cut away—as, for instance, in the gear-ring 31 the outer periphery is grooved, thereby leaving a flange to be engaged by the lugs at one side and sufficient metal at the other side to form the ball-race. The gear-pins 32 and the upper end of the tool-holder 40 are also bored out, as indicated by broken lines, to reduce weight.

The casing after the parts are all assembled is made oil-tight by the joints in the head 2, so that the reducing-gear may be run in a body of oil inserted in the casing, a removable plug being provided in the top of the casing at 42 for the purpose of renewing the oil from time to time. The oil in the casing is also brought into contact with all parts of the engine, thereby insuring perfect lubrication of all running parts.

It will be noted that by my arrangement 85 of the gear-head 33 and the manner of attaching the tool-holder 40 thereto said holder is brought up close to the driving-pinion 28, thereby enabling me to materially reduce the distance over all between the end of the tool-holder and the point of the feed-nut, which is an essential requirement in this class of tools. When the tool is in operation, the back pressure on the tool-holder forces the gear-head 33 against the ball-bearing between it and the gear-ring 31 and relieves the gear-head from frictional contact with the bearing-ring 34. Moreover, by reason of the form given to the ball-races the pressure on the balls is parallel to the thrust on the tool-holder and there is therefore no wedge action between the balls and the ball-races, and consequently no binding between the running parts of this bearing.

As the bearings 16 and 18 are in one piece 105 with the crank-pin, the running parts of the engine are supported upon a perfectly rigid base, and there can be no displacement or derangement of the several parts of the motor, as I have coupled them together. In order 110 to place the cylinders upon the crank-pin, I provide a split bushing for the hub of the cylinders, the bore of said hub being sufficiently large to permit the hub to be passed over the small bearing 18 to its place upon the crank-pin. The bushing is inserted after the cylinder-hub is in place on the crank-pin, this construction of the parts being the same as that which I have described and claimed in an application for Letters Patent of the United 120 States for improvements in air-compressors, filed of even date herewith.

Having thus described the several parts and details of construction of my improved tool-stock, what I claim as my invention, and 125 desire to secure by Letters Patent, is—

1. In a pneumatic-motor tool-stock, the combination of a casing having a motor secured to one of its heads, admission and exhaust passages leading from the motor 130

through the head and down the shell of the casing to a chambered boss formed thereon, a throttle-valve in said chamber, a sleeve through which air is admitted to the valve, 5 said sleeve acting as one of the handles of the tool-stock, and means on said sleeve for shifting the valve to shut off or change the direction of flow through the said passages.

2. In a pneumatic-motor tool-stock, the combination of a casing having a head formed integrally therewith, a motor secured to said head within the casing, admission and exhaust passages leading from the motor through the head to corresponding passages formed 10 on the head and extending down one side of the shell of the casing, a handle-boss having a valve-chamber into which said passages lead, a valve in said chamber, a sleeve extending out from said boss through which air 15 is admitted to the valve and which also serves as a handle for the tool, and means on said sleeve for shifting the valve to shut off or change the direction of flow through the said 20 passages.

25 3. In a pneumatic-motor tool-stock, the combination of a casing having a boss formed on the inside of one of its heads, a crank-pin with side bearings for a rotary reciprocating-piston motor secured to said boss by means 30 of a stud passing through the boss, a cup-shaped nut on said stud entering a cavity at the outer side of the casing-boss, a feed-screw screwed onto the stud against said nut, and a feed-nut adapted to be run down into the 35 cavity of said nut.

4. In a pneumatic-motor tool-stock, the combination of a crank-pin with side bearings formed at each end, side frames journaled on said bearings, a plurality of cylinders 40 journaled on the crank-pin between the side frames, connections between the side frames and cylinders whereby rotation is imparted from one to the other, a hub on one of the side frames projecting beyond its bearing, a pinion having teeth engaging corresponding notches in an inturned flange at the end of said hub, and a screw inserted in the hub to secure the pinion in place, said screw 45 having its head positioned between the end 50 of the bearing and the flange when the parts are assembled.

5. In a pneumatic-motor tool-stock, the combination of a casing, a motor within the casing, a driving-pinion on the motor, a gear-head in line with said pinion journaled in a 55 removable head of the casing, gears carried by the gear-head meshing with the pinion, a gear-ring inserted in the casing with which said gears also mesh, said gear-ring being 60 held in place on one side by projections formed on the casing-shell and on the other side by a thrust-bearing between it and the gear-head, and means to lock the gear-ring against rotation in the casing.

65 6. In a pneumatic-motor tool-stock, the

combination of a casing, a motor within the casing, a driving-pinion on the motor, a gear-head in line with said pinion, a casing-head provided with a packing-box through which a hub on the gear-head passes, an angular 70 hole in said hub, a tool-holder fitted in said hole, a lock-nut by which the tool-holder is fastened in the hub, a stationary gear-ring in the casing, gears carried by the gear-head in mesh with the driving-pinion and gear-ring, 75 and a thrust-bearing between the gear-head and gear-ring.

7. In a pneumatic-motor tool-stock, the combination of a motor and reducing-gear 80 inclosed in an oil-containing casing, a gear-head for the reducing-gear provided with a thrust-bearing within the casing and with an outwardly-projecting hub, a head for the casing provided with a packing-box through which said hub passes, a tool-holder shaped 85 to fit into an inwardly-closed socket provided therefor in said hub, and means for fastening the holder in the socket.

8. In a pneumatic-motor tool-stock, the combination of a motor and reducing-gear 90 inclosed in an oil-containing casing, a gear-head for the reducing-gear provided with an outwardly-projecting hub, a head for the casing provided with a packing-box through which said hub passes, an angular hole at the 95 inner end of said hub, an oil-tight closure for said hole, a tool-holder having an angled shank to fit said hole, and a lock-nut by which said tool-holder is fastened in the hub.

9. In a pneumatic-motor tool-stock, the 100 combination with a motor inclosed within a casing, of a reducing-gear comprising a pinion on the motor, a stationary gear-ring secured to the shell of the casing, a gear-head journaled in one of the casing-heads, gears 105 carried by said gear-head in mesh with the pinion and gear-ring, and a thrust-bearing between the gear-head and gear-ring comprising balls running in ball-races formed on the outer and inner peripheries of the gear-head and gear-ring respectively, the bearing-surfaces of said ball-races lying in planes at 110 right angles to the axis of rotation.

10. In a pneumatic-motor tool-stock, the combination, with a gear-head carrying the 115 reducing-gear, of a thrust-bearing therefor comprising balls and ball-races, the ball-races being formed on the gear-head at its outer periphery and on a stationary member of the tool-stock with their bearing-surfaces lying 120 in planes at right angles to the axis of rotation.

11. In a pneumatic-motor tool-stock, the combination of a casing-shell having a head formed integrally therewith, ridges formed 125 on the outside of the head and shell and extending from near the center of the head to a valve-chamber at the side of the shell, passages for the admission and exhaust drilled into said ridges to form continuous passages 130

from inside the head to the valve-chamber; the open ends where the passages intersect being closed by suitable plugs.

12. In a pneumatic-motor tool-stock, the combination, with the casing, of a gear-ring adapted to be inserted through the open end of the casing, and means within the casing to secure the gear-ring against rotation therein comprising a toothed plate fastened to the

casing and engaging corresponding notches in the periphery of the gear-ring.

In testimony whereof I have affixed my signature in presence of two witnesses.

FREDERICK W. PARSONS.
